[57] CLAIM

The ornamental design of a industrial robot, as shown and described.

DESCRIPTION

FIG. 1 is a front elevational view of an industrial robot showing our new design;

FIG. 2 is a side elevational view taken from the right of FIG. 1, the side opposite being a mirror image thereof;

FIG. 3 is a top plan view thereof;

FIG. 4 is a bottom plan view thereof;

FIG. 5 is a rear elevational view thereof; and

FIG. 6 is a perspective view thereof.

*FIG. 1**FIG. 2**FIG. 3**FIG. 4**FIG. 5*

FIG. 6.
